[57] CLAIM

The ornamental design for a personal computer enclosure, as shown and described.

DESCRIPTION

FIG. 1 is a front, top and right side perspective view of the personal computer enclosure showing our new design;

FIG. 2 is a front elevational view thereof on an enlarged scale;

FIG. 3 is a right side elevational view thereof on an enlarged scale;

FIG. 4 is a left side elevational view thereof on an enlarged scale;

FIG. 5 is a top plan view thereof on an enlarged scale;

FIG. 6 is a back elevational view thereof on an enlarged scale; and,

FIG. 7 is a bottom plan view thereof on an enlarged scale.

The broken lines are shown in the views for illustrative purposes only and form no part of the claimed design.

FIG. 2

FIG. 3

FIG. 4

FIG. 5

FIG. 6

FIG. 7
